UNITED STATES PATENT OFFICE.

CHARLES F. KETTERING AND WILLIAM A. CHRYST, OF DAYTON, OHIO, ASSIGNORS TO THE DAYTON ENGINEERING LABORATORIES COMPANY, A CORPORATION OF OHIO.

ELECTRICAL SYSTEM FOR ENGINES.

1,272,055.

Specification of Letters Patent.

Patented July 9, 1918.

Application filed July 16, 1914, Serial No. 851,259. Renewed December 5, 1917. Serial No. 205,668.

To all whom it may concern:

Be it known that we, CHARLES F. KETTERING and WILLIAM A. CHRYST, citizens of the United States of America, residing at Dayton, county of Montgomery, and State of Ohio, have invented certain new and useful Improvements in Electrical Systems for Engines, of which the following is a full, clear, and exact description.

10 The present invention relates to an improvement in electrical systems of generation, distribution and control, and is especially adapted for use in conjunction with vehicles of the type wherein a prime mover 15 or power generator, such as an internal combustion or explosion engine, or in fact any power element is utilized which requires an initial starting movement to be transmitted thereto, in order to bring the same into operation under its own power. Then this engine, when operating under its own power, is used to store up energy for future starting operations and for other purposes.

As an example of the above, the present 25 invention may comprise a dynamo electric machine adapted to be operated as a motor, in order to transmit power to the power generator for starting purposes, or as a generator, to furnish current for charging the 30 storage battery or accumulator, or to supply current to an ignition system which is installed on, and which furnishes ignition to the explosion or combustion engine used as a prime mover or power generator.

35 As a more specific example of the above, the invention may comprise a generator of the shunt-wound type, and an ignition system which comprises mechanism for automatically adjusting or changing the time of 40 occurrence of the sparking impulses, in order to furnish ignition to the engine at exactly the proper time.

The timing of the ignition will, of course, vary with the engine conditions.

45 However, it will be understood that where ignition systems are supplied with a constant source of current and where this current is of a substantially constant voltage, the wattage or intensity of the current 50 through said system, will be substantially reduced at high speeds. This reduction of the current flow at high speeds is due to the fact that the timing device of the ignition system is, of course, operated much faster 55 than when the system is operated at low

speeds; and therefore the main circuit is closed by said timing device for a shorter period of time at high speeds than at low speeds.

This will result in a less amount of current passing through the primary winding of the induction coil, embodied in the system, and it will therefore take a longer period of time for said coil to build up sufficiently to perform its required functions. 60

From the above it will be seen that the tendency will be to decrease the intensity of the ignition spark at high speeds, when properly the intensity of the spark should increase or at least remain constant with 70 increased speeds.

One of the objects therefore of the present invention is to increase the intensity of the ignition, as the speed of the engine increases, and the present description and 75 illustration sets forth means for accomplishing this object.

More specifically, this means comprises a common rheostat adapted to be connected with the shunt field of the generator, and 80 also in series with the ignition circuit.

It is well known in the combustion and explosion engine art, that as the speed of the engine increases the time of occurrence of the sparking impulses in the ignition system should be advanced in order to provide 85 proper ignition.

The present invention provides an automatic means for varying the time of occurrence of the sparking impulses in accordance 90 with the varying speeds of the engine, so that the ignition spark will take place at the proper time.

It is therefore one of the objects of the present invention to combine this automatic 95 spark control with means whereby the output of the electrical machine may be controlled and the intensity of the igniting spark varied in accordance with engine conditions.

More specifically, this automatic spark control means will cut resistance into the shunt field circuit of the electric machine and thereby control the output of the machine, and concurrently cut this resistance 105 out of the ignition circuit, in order to increase the intensity of the sparking impulses.

By the above operation, it will be seen that a common speed responsive control, will govern the intensity of the sparkings in

2
pulses in the ignition circuit, as well as to limit and regulate the maximum output of the electric machine.

From the above statement, the objects of the invention may be stated broadly to be as follows:—

To provide a plurality of electrical systems, the functions of each of which are substantially different, combined with a common system of control, whereby desired regulations of each of the systems in question may be affected.

A still further object of the present invention is to provide an ignition system, wherein a predetermined amount of resistance is included, and means operable to reduce the amount of resistance as the speed of the engine increases, so as to increase the flow of current through said system as the speed increases.

Further objects and advantages of the present invention will appear from the following description, reference being had to the accompanying drawings wherein one preferred form of the present invention is clearly illustrated.

In the drawings:—

Figure 1 is a diagrammatic view of the electrical circuits and connections, which may be employed in the present invention.

Fig. 2 is a fragmentary plan view of an automobile chassis, including an engine, and clearly illustrating the position and relative location of certain of the units comprising the present invention.

Figs. 3 and 4 are front and rear end views respectively, of the dynamo electric machine.

Fig. 5 is a top plan view of the electric machine, shown in Figs. 3 and 4.

Fig. 6 is a detail view of the front end housing of the electric machine.

Fig. 7 is a view partly in elevation and partly in section of the casing shown in Fig. 6, also disclosing the mechanism normally contained therein.

Fig. 7^a is a detail view of the resistance unit shown in Fig. 7.

Figs. 8, 8^a and 8^b illustrate modified forms of the structure shown in Fig. 7.

Fig. 9 is a detail view in elevation of part of the ignition controlling mechanism.

Figs. 9^a, 9^b, 9^c and 9^d are detail views of the parts comprising the structure shown in Fig. 9.

Fig. 10 is a view in elevation of the ignition controlling switch.

Fig. 10^a is a detail view of the cam element and operating buttons, embodied in the ignition switch, shown in Fig. 10.

Referring to the drawings and more particularly to Figs. 1 and 2, it will be noted that the present invention is illustrated as being installed on a motor vehicle, which may be of any approved type.

The side frames of the vehicle chassis are

indicated by the numerals 20, while the engine 21 is suitably supported therebetween, by means of the cross-supporting elements 22.

The dynamo electric machine 23, which forms what might be termed the prime mover in the present system, is preferably mounted adjacent to the engine, as is clearly shown in Fig. 2.

This electric machine is adapted to be connected with the engine and then operated as a motor for starting purposes. As soon as the engine becomes self-actuating, the means for coupling the electric machine to the engine for starting purposes, is disconnected, and a different set of coupling mechanism connects the electric machine to the engine, whereby the said machine is operated as a generator to store up power in a suitable accumulator for future starting operations, or to supply current for ignition, lighting or any other desirable purposes.

The connections for coupling the electric machine to the engine for starting purposes, are substantially the same as those illustrated and described in the copending applications of Charles F. Kettering, Serial No. 633,443, filed June 15, 1911; Serial No. 721,237, filed September 19, 1912; Charles F. Kettering and William A. Chryst, Serial No. 778,934, filed July 14, 1913; Serial No. 789,641, filed September 13, 1913; and Serial No. 846,911, filed June 24, 1914.

Inasmuch as the aforesaid connections and coupling means do not form a part of the present invention, further description and illustration thereof will be omitted in the present application, except where reference to the same is necessary to a clear understanding of the present invention.

As has been stated heretofore, the present invention includes an electric generating system and an ignition system, which in the present instance supplies ignition to the same combustion engine which operates the electric machine of the generating system.

This generating system in the present instance, comprises an electric machine 23 capable of operation as a shunt-wound generator.

It is a well known characteristic of generators of this type, that as the speed thereof increases, the electrical output also increases directly in proportion.

The ignition system mentioned above is of the constant source type; that is, the intensity of the energy supplied to the ignition system, does not materially change in accordance with the changes in the engine speed, but remains practically constant.

It is also characteristic of ignition systems of this type that as the speed of the engine increases, the amount of current which will flow through the ignition circuit will ordinarily be reduced. This is due to

the fact that the engine actuated timer which is employed to intermittently open and close the ignition circuit, in order to generate the sparking impulses, will close the said circuit for a shorter period of time at high speeds than it will at low speeds, inasmuch as this timing mechanism is geared to and driven directly or indirectly by the engine at a predetermined ratio of speed thereto.

As has already been stated heretofore, it is one of the objects of the present invention to provide controlling mechanism for regulating the electric machine, when used 15 as a generator, and also for controlling the ignition system, so that the intensity of the current flowing through the ignition system will increase as the speed of the engine increases.

20 This mechanism for controlling the electric machine, comprises means whereby the field intensity of the electric machine may be regulated as the speed of the machine varies, and this same means so actuated as 25 to control the intensity and wattage of the ignition system in accordance with the variations in engine speeds and conditions.

In regard to an ignition system, such as is embodied in the present invention, it is 30 desirable to provide for automatically controlling the time of occurrence of the sparking impulses, relative to the speed of the engine to which the ignition is being furnished.

35 This means for automatically controlling the time of occurrence of the sparking impulses, may be operable automatically in response to the varying speeds of the engine, and it is this same speed responsive means 40 which is connected up with the mechanism for controlling the generator, and also for controlling the ignition system as described above.

Referring to the drawings, it will be seen 45 that the electric machine 23 is operated as a generator through the shaft 24, which is in turn driven by the engine through the medium of the train of gears 25, and will tend to operate the ignition mechanism 50 through the driving gear wheel 29, (see Fig. 7), which preferably forms one element of a frictional clutch, interposed between the dynamo electric machine 23 and the timing gears 25.

55 This clutch is substantially the same as that shown and described in our co-pending application, Serial No. 846,911, filed June 24, 1914, and as the structure and functions thereof have been specifically described, 60 illustrated and claimed in said co-pending application, no detail description of the same will be given in the present case, unless it becomes necessary to an understanding of the present invention.

65 However, with further reference to the

gear wheel 29; it will be seen that it is provided with spiral teeth 30, which mesh with the pinion 31, and forms direct driving means from the engine to the movable elements of the ignition system, as will be 70 described hereinafter.

The pinion 31 is mounted upon a sleeve 32, which in turn is slidably mounted upon the central shaft 33. The shaft 33 forms the main shaft of the ignition control mechanism, and is mounted within a compartment formed in the front end housing 34, on the bearings 35 and 36.

The sleeve 32 which carries pinion 31 is provided with a straight slot 34', through 80 which the pin 35, carried by the collar 36, passes. This pin 35 also passes through the angular slot 37, formed in the shaft 33.

The collar 36 is provided with a grooved periphery as at 38, wherein a yoke member 85 39 (see Fig. 9) is adapted to fit. This yoke member is preferably connected to a manually operated mechanism described hereinafter.

The pinion 31 and the sleeve 32 are, of 90 course, secured together in a determined fixed relation by means of the screws or other securing devices 40.

The rod 33 is preferably of hollow construction, and is adapted to receive one end 95 of the cam carrying element 41. This element comprises a shaft 42 and a projecting collar 43, shown in Figs. 7, 8 and 9.

Above the collar 43, a cam 44, having a suitable number of lobes 45, is formed on or 100 secured to said element 41. This cam 44 is so positioned that when it is rotated, it will tend to intermittently close and open the contacts 46 and 47.

The element 41 extends upwardly beyond 105 the cam 44, terminating in a stub shaft 48, which carries a rotor 49 of a suitable distributing system; said rotor co-operating with a head 50, to control the secondary 110 circuits of the ignition system in a manner well understood to those skilled in the art.

The shaft 42 of the element 41 is provided with an angular slot 52, a portion of which is held in alignment with the straight slot 53, 115 formed in the upper portion of the central shaft or rod 33, by means of a pin 54, which passes through both of said slots.

From the above description, it will be seen that if the yoke member 39 is operated 120 by the manually controlled means, such as is shown in the co-pending application of Charles F. Kettering, Serial No. 628,812, filed May 22, 1911, and U. S. Patent of Charles F. Kettering, No. 1,040,349, granted 125 October 8, 1912, the collar 36 will be moved vertically on the shaft 32. This will also effect the vertical movement of the pin 35, and inasmuch as the said pin will move through both the vertical slot 34' and the 130

angular slot 37, a movement of the shaft 33 relative to the sleeve 32 will occur inasmuch as said sleeve is maintained in a fixed position by the enmeshment of the pinion 31 with gear wheel 29.

5 The movement of the shaft 33 will also actuate the cam 44, relative to the contact elements 46 and 47, and will therefore tend to advance or retard the time of closing and opening the primary circuit of the ignition system, and thereby control the time of occurrence of the sparking impulses.

10 The adjusting of the time at which the 15 sparking impulses should take place in the ignition system by manual means, is an operation which requires much skill and close accuracy on the part of the operator, in order to secure the most advantageous results from the ignition system.

20 It is therefore an advantage to provide for automatically controlling this adjusting of the ignition, and there is provided in the present invention, a means for automatically adjusting the time of occurrence 25 of the sparking impulses. This means comprises a centrifugal operating element 60, which is pivoted to the shaft 33, at the point 61, and is connected to the pin 54 which has been described heretofore as passing through angular slot 52 and the straight slot 53, formed respectively in the element 30 41 and the rod 33.

This pin 54 is preferably carried by the sleeve 66, which has a projecting flange 67 forming one abutment for the spring 68, which is interposed between the said sleeve 66 and the shoulder 43 of the cam carrying element, when the parts are in assembled position.

35 40 The function of the spring 68 is to maintain the centrifugal member in an ineffective position, such as is shown in Figs. 7 and 8.

Now, as the speed of the engine 21 increases, the speed of the shaft 33 will also increase, and this will be transmitted in 45 turn to the centrifugal member 60, by means of the connections heretofore described, in such a manner that the said weight will 50 tend to fly out and come to a balanced position.

Now, as the weight tends to assume this balanced position, the arm 62 will be moved upwardly, and this in turn will force the 55 sleeve 66 in the same direction, whereby the pin 54 will be moved through the slots 53 and 52 respectively, which will cause a movement of the cam carrying element 41, relative to the shaft 33, thus advancing or 60 retarding the movement of said cam, in a manner similar to that described heretofore in connection with the operation of the manually controlled means.

The collar 66, described heretofore, is 65 provided with a peripheral groove 70,

wherein a bearing member 72, shown in dotted lines in Fig. 7, is positioned. This bearing element is carried by the arm 73, one end of which is pivoted as at 74, to one of the walls of the end housing 34.

The opposite end of said arm is formed into a contact wiper 75, clearly shown in Fig. 7, and lies in such position that it will pass over the resistance spool or reel 76, at such times as the said arm is moved by the operation of the centrifugal member 60. The wiping portion of the arm 73 may be integral therewith, or separate therefrom, and secured to said arm in any suitable manner.

80 The resistance reel or spool 76 is formed of suitable insulating material and is preferably grooved, as is shown in Fig. 7, to receive a resistance wire 77, the opposite terminals of which are connected to the terminal posts 78 and 79 respectively, by means of the contacts 103 and 104.

In order to prevent undue wear of the resistance wire or material 77, mechanism is provided whereby the said spool or reel 90 will be actuated as to present intermittently different surfaces of said resistance wire or material for the contact wiper 75 to pass over, thus substantially distributing the wear over the entire resistance.

95 This mechanism comprises a pawl 80, pivotally mounted at 81 in such a manner that as the lug 82, carried by the arm 73, reaches its maximum upward movement, said pawl will be tripped so as to engage with the teeth 84, formed on the upper end of the spool 76, and thus impart a slight rotative movement to said spool.

100 Any suitable means may be provided to prevent the operation of the spool 76 in a direction other than that in which the pawl 80 tends to move the same.

105 In Fig. 8, a slightly modified form of the controlling mechanism heretofore described, is clearly shown. In this arrangement, the 110 peripheral groove 70, formed in the sleeve 66, receives lugs 90, connected with a yoke member 91. This yoke member is also connected with a pivoted rod 92, which carries a wiper 93, which has substantially the same 115 functions as the wiper 75.

120 From the above, it will be seen that as the centrifugal element 60 is actuated in response to the speed of the shaft 33, the yoke member 91 will be oscillated in such a manner as to cause the wiper 93 to pass over the resistance winding 76.

125 By referring to Fig. 6 of the drawings, wherein a detail view of the front end housing is illustrated, it will be noted that the said housing 34 is divided into a plurality of compartments, arranged in certain relative positions, whereby the units contained in the various compartments are enabled to coöperate in an advantageous manner. This con-

struction also facilitates the assembling of the various coöperating units and permits of a compact structure which occupies only a small amount of space.

5 In the compartment 100, as has been stated heretofore, the elements shown in Fig. 9 are mounted so that the pinion 31 will lie adjacent to the compartment 101, wherein the clutch mechanism shown in Fig. 7 is contained.

10 These compartments are inter-communicating so as to permit the teeth of the pinion 31 to engage with the driving pinion 30.

15 The compartment 102 is adapted to contain the resistance unit 77 and is provided with slightly resilient mounting plates 103 and 104, which are so positioned that they readily permit the insertion of the resistance unit 77 therebetween, in such a manner as to 20 hold the same securely in place.

These plates 103 and 104 are of conductive material and form a part of the circuit which includes the resistance winding 77.

25 In the co-pending application Serial No. 782,886, filed August 4, 1913, there is shown, described and claimed a resistance unit which is included in the ignition circuit at all times.

30 In the present invention, an arrangement similar in certain features to the one included in the above-named application, is also provided, but is so combined with certain other features to be described herein-after, that its functions are considerably 35 altered.

In the present invention, referring to Fig. 7, the resistance unit 106 is shown as mounted upon the exterior of the end housing 34, see Fig. 7, and adjacent to the terminal 78.

40 As will be seen hereinafter, this resistance unit is combined with a controlling mechanism for the generator and ignition system, in such a manner that up to a predetermined speed, said unit remains effectively in the 45 ignition circuit, but from this predetermined point of speed onward, the said unit is entirely cut out of the ignition circuit.

By referring to Figs. 8 and 8^a, a slight modification of the invention shown in Fig. 50 7 is set forth. In this arrangement, the unit 106 is mounted upon the same core which carries the resistance winding 77, but in this form of the invention, the resistance 77 and the unit 106 are insulated from each other 55 by means of a suitable insulating block 107.

The functions of the above described resistances, as well as the other parts previously described, will be more clearly understood from the following description of the 60 functions and workings of the system, as set forth in Fig. 1.

In this figure, it will be seen that the electric machine 23 comprises a motor series winding 120, and motor commutator brushes 65 121 and 122 respectively, which are brought

into contact with the motor commutator 123 at such times as the electric machine 23 is being operated as a motor for starting purposes.

The functioning of the machine as a motor, and the structure thereof, has been clearly described in our co-pending application, Serial No. 846,911, filed June 24, 1914, and therefore no further description of the same will be given in the present case, unless it becomes necessary to a clear understanding of the present invention.

70 The electric machine 23 includes, besides the series winding, a shunt winding 124 together with the generator commutator 80 brushes 125 and 126 respectively, which are at all times in contact with the commutator 127. This commutator is entirely separate and apart from the motor commutator 123.

75 The battery 128 is adapted to be connected with either the motor or generator windings of the machine 23, through the operation of certain switch mechanism, which will be described hereinafter.

80 When the machine is to be operated as a motor for starting purposes, one of the controlling elements 129 or 128 of the switch 180 is pulled outwardly in the direction of the arrow shown in Fig. 1, which operation will tend to actuate the sliding plate 95 131^a (see Fig. 10) and close the contact plates 130 and 131 respectively.

85 This will permit current to flow from the battery 128, through the wire 132 to the point 133, thence through wire 134 across 100 the contact plates 131 and 130, through the wire 135, to the point 136, at which point the current will branch, a portion thereof passing through wire 137, across the generator brushes 125 and 126 to the wire 138, 105 and across the contact plates 139 and 140 respectively to the ground connection 141, thence back to the battery, via ground connection 142.

90 The remainder of the current will pass 110 from the point 136 through the shunt field 124, across the resistance 77 to the arm 73, thence back to the opposite side of the generator circuit, via ground 145 to the ground 141.

115 Supposing that the switch element 129 is the one which has been moved in the direction of the arrow shown in Fig. 1, the same operation which closed the above described circuit will also close the following 120 circuit:

125 From the point 133, through the wire 150, contact plate 151, the conductive portion 152 of the switch element 129, contact element 153, from there to the wire 155, thence through the primary winding 156 of the induction coil, through the timing mechanism 157, wire 158 to the point 159. At this point, the current will branch, the greater portion thereof, under the condition shown 130

in Fig. 1, passing through the resistance unit 106, to the ground 107, while a small portion of the current will pass through the wire 160, through the resistance turns 77 to the arm 73 to ground 145.

From the above, it will be seen that a circuit through the generator windings will be closed simultaneously with the closing of the ignition circuit. This operation of the electric machine 23 as a motor, by passing current through the generator windings thereof, has been clearly described in our co-pending application Serial No. 846,911, filed June 24, 1914, and is adapted to impart an initial operation to the electric machine 23 as a motor.

This initial movement of the machine as a motor has less torque effect and is generally at a lower speed than when the machine is operating as a motor for starting purposes, in order to permit the coupling up of the electric machine to the engine, by means of the shiftable gearing 144.

As soon as this initial movement has been imparted to the electric machine, the operating pedal 165 is operated to shift the gearing 144 and to actuate the rod 166, see Figs. 1 and 2, whereby the motor brush 122 will be brought into contact with the commutator 123, and the contact plates 139 and 140 will be separated, thus breaking the generator armature circuit. At this point, current will flow from the battery, through the series winding 120, across the brushes 121 and 122, back to the battery, via grounds 141 and 142.

However, it will be noted that the circuit through the shunt field of the generator was initially closed by the operation of the element 129, and this circuit remains closed, thus being accumulative in effect, relative to the series winding.

As soon as the engine becomes self-actuating, the pedal 165 is released, thereby permitting the contact plates 139 and 140 to close and the motor brush 122 to be moved out of contact with the commutator 123.

Now, as soon as the engine speed becomes greater than the predetermined ratio of speed between the engine and the electric machine, the friction clutch illustrated in Fig. 8 will be brought into effect to couple the electric machine to the engine, whereby said machine will be operated as a generator.

From the above, it will be seen that the following circuit will be closed as long as the pull button element 129 of the ignition system is maintained in its outward position:

From the generator commutator 127, the current will flow through the brush 125 to the point 136, where one side of the field winding of the generator is cut in. Of course, a portion of the current will divert and pass through the generator field wind-

ing 124, and across the resistance 77, contact wiper 73, ground 145, to the opposite side of the generator, via the ground connection 141, contact elements 140 and 139 respectively.

The charging current will pass from the point 136 to the battery, via the wire 135, contact plates 130 and 131, branch wire 134 and wire 132, through the battery and from there back to the opposite brush of the generator, through the grounds 142 and 141, contact plates 140 and 139 respectively, and wire 138 to the brush 126.

Exactly the same operation and functioning of the other units will take place if the pull button element 128 is operated instead of the element 129, with the exception that the dry batteries 170 will form the source of ignition current through the following circuit:—

From the batteries 170, through wire 171, contact plates 172 and 173, to the wire 155, from which point the circuits will be substantially the same as heretofore described with reference to the circuits affected by the operation of the pull button element 129.

As has been stated heretofore, the electric machine 23, when used as a generator, is of the shunt wound type, and it is one of the characteristics of generators of this type that as the speed thereof increases, the electrical output also increases in proportion.

In the present system, where the electric machine, when used as a generator, is adapted to store up power in a suitable accumulator, it is desirable to regulate the maximum output of the generator, so that overcharging of and damage to the battery will be substantially eliminated.

In the present instance, the resistance 77 is normally cut out of the shunt field, due to the initial or normal position of the contact wiper 75, but as the speed of the engine increases, the centrifugal element 60 of the controlling mechanism will so operate as to move the wiper 75 over the turns of resistance 77, and thus cut in said resistance directly in proportion as the speed increases, whereby the intensity of the field 124 will be controlled so as to maintain a predetermined maximum output of the generator, regardless of the various speeds at which the generator may be operating.

This same resistance 77 is so connected with the ignition circuit, see Fig. 1, that it forms a parallel path, together with the resistance unit 106, for the current flowing through said circuit, thus causing the current to branch through two separate paths, each of the said paths containing a predetermined amount of resistance, and in the present case it may be stated that the resistance 106 is less in value than the resistance 77. Therefore, a greater amount of current will pass through the path containing the

resistance 106, than the path embodying the resistance 77. These resistances, of course, are so proportioned that the current flow through said circuits will initially give the 5 proper sparking impulses for low speeds of the engine.

Now, as the element 73 is actuated by the centrifugal element 60 to cut resistance into the shunt field of the generator, it will also 10 reduce the amount of resistance in one of the paths of the ignition, whereby the current will tend to flow through said paths more evenly.

This equalizing of the flow of current will 15 continue until the arm 73 reaches the point 175, at which time both the resistance units 77 and 106 will be entirely cut out of the ignition circuit, inasmuch as the current will pass directly from the wire 160 through the 20 contact wiper 75 to ground, thus completing the ignition circuit.

As is shown in dotted lines, it may be desirable to cut out the ignition resistance unit 106 and simply include the resistance 77 in 25 series with the ignition circuit, whereby, of course, the resistance will be cut out of the ignition circuit directly in proportion to the resistance cut into the field circuit, in response to the varying speeds of the engine.

30 One of the reasons for providing the ignition circuit with a predetermined amount of resistance is that a combustion engine does not require the same intensity of spark at low speeds of said engine as it does at 35 high speeds. The resistance units are therefore so proportioned that ignition sparking and proper intensity will be secured for low speeds of the engine, and then when this resistance value is cut down for increasing 40 speeds of the engine, of course, the intensity of the igniting sparks will also be increased to meet the required conditions.

In the switch assembly shown in Figs. 10 and 10^a, it will be noted that the dimmer 45 element 181 has been mounted thereon, and comprises a coil of resistance wire 182, which may be cut into the head light circuit, thus cutting down the amount of current passing to the head lights, and thereby dimming or 50 cutting down the lighting effect thereof.

From the above description it will be seen that the present invention embodies a single means for controlling the electric machine when operating as a generator, and also controlling and regulating the ignition system, 55 in order to regulate the ignition in a desired manner, in accordance with the various engine conditions.

While a preferred form of the present invention has been shown and described, it should be understood that this form of the invention has been simply selected for the purpose of illustrating one manner in which the invention can be carried into effect, and 60 the right to change or alter the units or

combinations of units comprising the said invention, as may come within the scope of the appended claims, is reserved.

What we claim is as follows:—

1. In a system of electrical distribution and control, the combination with a generator and circuit connections, and an ignition system having a sparking circuit; of automatic means for varying the time of occurrence of the sparking therein; and means operable by said automatic means for controlling the output of said generator. 70

2. In a system of electrical distribution and control, the combination with a current generating system, and an ignition system; of means operable to control the output of the generating system, and the intensity of the current flowing through the ignition system. 80

3. In a system of electrical distribution and control, the combination with a current generating system, including an electric generator and an ignition system; of a common means for controlling the output of the generating system, and the current flowing 85 through the ignition system. 90

4. In a system of electrical distribution and control, the combination with a combustion engine; of a generating system including a generator, comprising a field winding; an ignition system for said engine; and means operable by said engine, for varying the field intensity of said generator, and increasing the flow of current through said ignition system, as the speed of the engine 95 increases. 100

5. In a system of electrical distribution and control, the combination with a combustion engine; of a generating system including a generator; an ignition system for said engine; and means for varying the field intensity of said generator, and the intensity of the ignition in accordance with the speed of the engine. 105

6. In a system of electrical distribution and control, the combination with a current generating system, and an ignition system; of speed responsive means operable to control the output of the generating system, and the wattage passing through the ignition 110 system. 115

7. In a system of electrical distribution and control, the combination with a combustion engine, of a current generator operated thereby; an ignition system for said engine; 120 and means for controlling the current flow through said ignition system, and for limiting the output of the generator as the speed of the engine increases.

8. In a system of electrical distribution and control, the combination with a combustion engine; of a generating system including an electric machine, comprising a shunt field winding; an ignition system for said combustion engine; a resistance connected with 125 130

the generator field and also with the ignition system; and means for normally cutting out all of said resistance from the field circuit of the generator, and for initially maintaining a predetermined amount of the resistance in the ignition circuit.

9. In a system of electrical distribution and control, the combination with a combustion engine; of a generating system comprising an electric machine having a field winding; an ignition system comprising circuits for said combustion engine; a resistance connected with the field winding of the electric machine and the ignition system; and means responsive to the speed of the combustion engine for increasing the resistance in the field circuit of the generator, and to decrease the resistance in the ignition circuit as the speed of the engine increases.

20 10. In a system of electrical distribution and control, the combination with a combustion engine; of a current generating system, comprising an electric machine having a field winding, said machine being operated by the engine; an ignition system for supplying said engine with ignition, comprising a current source and circuit connections; a resistance connected with the field winding of the electric machine, and also included in the ignition circuit; means for normally cutting out all of said resistance from the field circuit of the electric machine, and for normally maintaining a predetermined amount of the resistance in the ignition circuit, and means responsive to the speed of the engine, to introduce the resistance into the field circuit of the generator, and to decrease the resistance in the ignition circuit, as the speed of the engine increases.

40 11. In a system of electrical distribution and control, the combination with a combustion engine; of a current generator comprising a field winding; an ignition circuit; a variable resistance, a portion of which is normally cut into the ignition circuit; and means responsive to the speed of the engine to gradually cut said resistance into the field circuit of the generator, to limit the output thereof, and to decrease the resistance in the ignition circuit to increase the flow of current therethrough, as the engine speed increases.

50 12. In a system of electrical distribution and control, the combination with an internal combustion engine; an ignition system including a predetermined amount of resistance; and means for varying said resistance as the speed of said engine varies.

60 13. In a system of electrical distribution and control, the combination with an internal combustion engine; of an ignition system therefor, including a main circuit having a predetermined amount of resistance therein; and means responsive to the speed

of the engine for decreasing the amount of resistance in said circuit as the speed of the engine increases.

14. In a system of electrical distribution and control, the combination with an internal combustion engine; of an ignition system therefor; a variable resistance, a determined amount of which is normally included in the circuit of the ignition system; and means operable to vary the time of occurrence of the sparking in said ignition system and to concurrently vary the amount of resistance in said circuit.

15. In a system of electrical distribution and control, the combination with an internal combustion engine; of an ignition system therefor; a variable resistance, a determined amount of which is included in the circuit of said ignition system; and means responsive to the speed of the engine to vary the time of occurrence of the sparks in the ignition system, and to concurrently vary the amount of resistance in said circuit.

16. In a system of electrical distribution and control, the combination with a generator and circuit connections, and an ignition system having a sparking circuit; of automatic means for varying the time of occurrence of the sparking therein; means operable by said automatic means for controlling the output of the said generator; and manually controlled means for varying the time of occurrence of the sparking in the ignition circuit independently of the automatic means.

17. In a system of electrical distribution and control, the combination with an internal combustion engine, of an ignition system therefor, including circuit connections; a timing device for intermittently opening and closing said connections; and means operable to vary the operation of said timing device and for varying the intensity of ignition current in accordance with the varying speeds of the engine.

18. In a system of electrical distribution and control, the combination with a plurality of generator and ignition circuits to be controlled; and a common means automatically operable to control both of said circuits.

19. In a system of electrical distribution and control, the combination with a generator circuit and a work circuit; of a resistance; and means for cutting said resistance into one of said circuits and concurrently cutting it out of the other of said circuits.

20. In a system of electrical distribution and control, the combination with a plurality of electrical circuits embodying working devices having different functions; of a resistance; and means for cutting said resistance into one of said circuits to control the working devices therein, and to concur-

- rently cut said resistance out of the other of said circuits to control the working devices therein.
21. In a system of electrical distribution and control, the combination with a generator and circuit connections, and an ignition system having a sparking circuit; and a common automatic means controlled by speed responsive means for controlling the 10 sparking circuit and the generator output.
22. In a system of electrical distribution and control, the combination with a combustion engine; of a generating system including an electric machine, an ignition system 15 for said combustion engine; and a resistance controlled by the speed of the engine for controlling said ignition system and said generator.
23. In a system of electrical distribution and control, the combination with a generator and circuit connections; and an ignition system having a sparking circuit; of a common automatic means for controlling said generator and ignition circuit; and 20 manual means for controlling said ignition circuit without controlling said generator.
24. In a system of electrical distribution and control, the combination with an ignition system having a sparking circuit; of 25 automatic means for controlling the timing of the sparking circuit; and manually controlled means for bodily moving the automatic means to vary the time of occurrence of the sparking in the ignition circuit in- 30 dependent of the controlling operation of the automatic means.
25. In a system of electrical distribution and control, the combination with a plurality of electric systems to be controlled; of 35 a resistance electrically connected with said systems; and automatic means responsive to conditions affecting said systems to cut varying portions of said resistance into the circuit of one of said systems and out of the 40 circuit of the other of said systems.
26. In a system of electrical distribution and control, the combination with a generator; of an ignition circuit electrically connected with said generator; and automatic 45 means for regulating the output of said generator and the resistance of said ignition circuit.
27. In a system of electrical distribution and control, the combination with a generator; of an ignition circuit electrically connected with said generator; and a common 55 automatic speed responsive means for regulating the output of said generator and the resistance of said ignition circuit.
28. In a system of electrical distribution and control, the combination with a generator; of an ignition circuit including means for varying the time of occurrence of spark- 60 ing therein, and a common means automati- cally operable to control the regulation of 65 said generator, the current of said ignition circuit and the operation of said means for varying the time of occurrence of the spark- ing.
29. In a system of electrical distribution and control, the combination with a generator, of an ignition circuit including means for varying the time of occurrence of spark- 70 ing therein, a common means automatically operable to control the regulation of said 75 generator, the current of said ignition circuit and the operation of said means for varying the time of occurrence of the spark- ing, and manually operated means connected with said common automatic means for 80 manually controlling the operation of the means for varying the time occurrence of the 85 sparking.
30. In a system of electrical distribution and control, the combination with an internal combustion engine of an ignition system therefor including a primary circuit, a timing device including an engine actuated cam and coöperating contacts intermittently opened and closed by said engine-actuated 90 cam, a resistance in said primary circuit; and automatic means for proportionately varying said resistance.
31. In a system of electrical distribution and control, the combination with an internal combustion engine, an ignition system including a timing device and a resistance; and automatic means for varying the resistance proportionately as the speed of the 95 timing device varies.
32. In a system of electrical distribution and control, the combination with an internal combustion engine, of an ignition system, a source of constant current; and automatic means for proportionately increasing 100 the strength of current in the ignition system as the speed of the engine increases.
33. In a system of electrical distribution and control, the combination of an internal combustion engine, an ignition system including a make and break device, a source of constant current, and a resistance, and means for decreasing the resistance proportionately to increase of the engine speed.
34. In a system of electrical distribution and control, the combination with an internal combustion engine of an ignition system therefor including a primary circuit; an engine actuated timing device having provisions for opening and closing said 115 primary circuit for intermittent time periods, a resistance included in the primary circuit, and automatic means for decreasing the resistance as the circuit closing period decreases.
35. In a system of electrical distribution and control, the combination with an internal combustion engine, of an ignition

- system therefor, a variable resistance, a determined amount of which is normally included in the circuit of the ignition system, a common automatic means operable to vary 5 the time of occurrence of the sparking in the ignition system and to concurrently vary the amount of resistance in said system, and manually operated means connected with said common automatic means for manually 10 controlling the operation of the means for varying the time occurrence of the sparking.
36. In a system of electrical distribution and control, the combination with an internal 15 combustion engine of an ignition system therefor including a plurality of resistances one of which comprises a thermal resistance and another of which comprises an automatically controlled resistance.
- 20 37. In a system of electrical distribution and control, the combination with an ignition system having a sparking circuit; of an ignition timer including an engine-driven member, a sleeve, a centrifugal governor 25 mounted on said sleeve, means including cam devices for transmitting movement from said centrifugal governor to said engine actuated member, and operable means for moving said sleeve to control the engine 30 driven member.
38. In a system of electrical distribution and control, the combination with an engine of a generator, an ignition system including an ignition timer, an engine-actuated 35 shaft for said timer, a regulator for said generator, and means mounted on said shaft for operating said regulator.
39. In a system of electrical distribution and control, the combination with an engine, a generator including a housing; of 40 an ignition system, and common automatic means contained in said housing for controlling said generator and ignition system.
40. In a system of electrical distribution and control, the combination with an engine, of an engine-actuated shaft, an ignition system including a timing member on said shaft, a sleeve, a centrifugal governor 45 mounted on said sleeve, means between said 50 governor and said sleeve to transmit movement from the governor to said timer member, a regulating means, means including a loose connection actuated by said governor for operating said regulating means, and 55 manually operated means for rotating said sleeve.
41. In an ignition system, including ignition circuit connections; an engine operated ignition device for opening and closing said 60 connections; automatic means for adjusting said device through a range of automatic adjustment; and independent means for adjusting said automatic means, while permitting said automatic means to adjust said de-
- vice through said range of automatic ad- 65 justment.
42. In an ignition system, the combination with primary and secondary circuits, of a timing device including coöperating contacts in said primary circuit; a distributing 70 device in the secondary circuit; an engine driven member provided with means for opening and closing the contacts in the primary circuit, and with means for driving the distributing device; manually controlled 75 means and automatic means, each for adjusting the engine driven member to correspond with changes in the time relation between the cycle of movements of the engine driven member and the engine cycle, said 80 manual means and said automatic means being capable of making adjustments, each independently of the other, but effecting a joint control of said engine driven member.
43. In an ignition system for internal 85 combustion engines, the combination with a timing device; of an engine driven member comprising end sections and an intermediate section joining the end sections, one of the end sections having provisions adapting it 90 to be driven by the engine, the other end section having provisions for actuating the timing device, the different sections of the engine driven member being capable of unitary movement; a means for causing relative movement of the intermediate section and one of the end sections; and a second means independent of the first means, for causing relative movement of the intermediate section and the other end section. 95
44. In an ignition system for internal combustion engines, the combination with a timing device; of an engine driven member comprising end sections and an intermediate section, including coöperating cam 100 portions for connecting said sections together in series to form a body capable of unitary movement; means for causing relative movement of the intermediate section and one of the end sections; and a second 105 means, independent of the first means, for causing relative movement of the intermediate section and the other end section, one of the end sections operating the timing device.
45. In an ignition system for internal combustion engines, the combination with primary and secondary circuits, of a timing device including coöperating contacts in said primary circuit, a distributing device 110 for the secondary circuit, an engine driven member comprising end sections and an intermediate section joining the end sections, one of the end sections having provisions adapting it to be driven by the engine, the other end section having provisions for opening and closing the contacts in the primary circuit, the different sections of the 115
- 120
- 125

engine driven member capable of unitary movement; manually operable means for causing relative movement of the intermediate section and one of the end sections, 5 and automatic means for causing relative movement of the intermediate section and the other end section.

In testimony whereof we affix our signa-

tures in the presence of two subscribing witnesses.
